UNITED STATES PATENT OFFICE.

OLAF ELTON, OF PORT WASHINGTON, WISCONSIN, ASSIGNOR TO GILSON MANUFACTURING COMPANY, OF PORT WASHINGTON, WISCONSIN.

GAS-ENGINE-CONTROLLING MECHANISM.

1,230,571.

Specification of Letters Patent. Patented June 19, 1917.

Application filed May 21, 1915. Serial No. 29,562.

To all whom it may concern:

Be it known that I, OLAF ELTON, a citizen of the United States, and resident of Port Washington, in the county of Ozaukee and State of Wisconsin, have invented certain new and useful Improvements in Gas-Engine-Controlling Mechanism; and I do hereby declare that the following is a full, clear, and exact description thereof.

10 My invention has for its general object to provide a simple, economical and effective mechanism for conjointly and independently controlling the spark mechanism and valve mechanism of an internal combustion engine.

15 Specific objects of my invention are to provide a valve-rod under spring control in one direction and cam-controlled in the opposite direction in conjunction with an independent rod connection for actuating the 20 spark mechanism also under spring-control in one direction and under cam control in the opposite direction, the said rods being arranged parallel with stop mechanism associated therewith whereby they are 25 jointly locked in one position through the action of a governor-controlled locking means associated with one of the rods;

To provide means in connection with the 30 igniter rod in the form of a notched segment, whereby the spark moment may be advanced, retarded or cut out, the movement being effected by a lever which is limited in its extreme movements by stop-ears that are formed upon the sector, and

35 To provide an anti-friction guide at the operating end of the igniter rod.

With the above and other minor objects in view the invention consists in certain peculiarities of construction and combination 40 of parts as set forth hereinafter with reference to the accompanying drawings and subsequently claimed.

In the drawings

Figure 1 represents a fragmentary plan 45 view of a controlling mechanism for internal combustion engines embodying the features of my invention, the said view being shown with parts removed and parts in section to more clearly illustrate structural features;

Fig. 2, a sectional elevation of the same, the section being indicated by line 2-2 of Fig. 1, with a governor-controlled stop-arm shown diagrammatically, the same being adapted to engage the valve-rod;

Fig. 3, a detailed sectional elevation of the

igniter mechanism, the section being indicated by line 3-3 of Fig. 1;

Fig. 4, a cross-section through the igniter actuating rod showing the means for advancing and retarding the sparking point, the section being indicated by line 4-4 of Fig. 2, and

Fig. 5, a detailed longitudinal sectional view of the advance and retard mechanism, the section being indicated by line 5-5 of Fig. 4.

Referring by characters to the drawings, 1 represents a portion of the engine-bed, to which is secured a housing bracket 2, which is also provided with journals for an arbor 3. The housing embodies a cap member 2', which is made in two parts for convenience in assemblage, the main cap member comprising a portion of the split bearing in connection with the housing while another section 2'' forms a closure for the neck portion of the housing, which neck portion is formed with longitudinal channels therein that constitute slide bearings for the head portions 4 and 5 respectively of an igniter rod and a valve-rod. These rods terminate with anti-friction rollers 4', 5', respectively, that are incased within the chambered portion *a* of the two-part housing. Said housing chamber also incases an igniter cam 6 and a valve-cam 7, which cams are secured to the arbor 3 that is driven by a gear-wheel 3' affixed thereto and adapted to mesh with a pinion, not shown, that is usually mounted upon the crank-shaft of an engine. The head portions 4 and 5 of each of these rods are connected to the housing neck by springs 8, 8', whereby the end rollers of 95 said rods are normally held in working engagement with their respective cams, motion of which cams is imparted to the rods in opposition to their spring-control. The main portion 5'' of the valve-rod is suitably guided at its outer end and is adapted to engage the lever of an exhaust valve, which lever is indicated by dotted lines in Fig. 1. The head portion 5 of the valve-rod also carries an adjustable tappet-plate 105 9, which is mounted upon a block 9' that constitutes part of the rod-head and this tappet-plate is arranged to engage the nose 10 of a stop-arm 10' which is suitably fulcrumed, the rear end of said arm being held into engagement with a reciprocative conical sleeve 11, the said sleeve being, as shown,

100

105

110

under governor control. The contact between the arm and sleeve is effected by a coiled spring 11', which connects the arm and thus serves to normally hold the nose 5 of the latter at a predetermined distance from the tappet-plate 9. The rods, as shown, are positioned parallel with relation to each other and the valve-rod head 5 is provided with a lug 12, which lug carries 10 a tappet member 12' that is arranged in the path of travel of a corresponding stop-block 12'' that is secured to the head portion 4 of the igniter rod. The head portion of said rod also has secured thereto 15 cheek-plates 13, the lower portions of which carry a pivot-pin 14 that serves as a fulcrum for arms 15 of an adjusting lever 15'. The arms of the lever are also connected by a fulcrum-pin 14' which projects through 20 slots 16 that are formed in the cheek-plates directly over the pivot-pin 14. The pivot-pin 14', which is carried by the lever-arms has mounted thereon between the cheek-plates 13, an oscillatory pitman section 4'' 25 of the igniter rod. The outer end of the pitman section carries a trip-dog 17, the nose 17' of which is arranged to engage a spring-controlled finger 18 that actuates the movable electrode 19 of a spark mechanism, the said electrode and finger being 30 mounted upon a spindle 20. The stationary electrode 21 is affixed to one wall 22 of the engine cylinder, which wall also constitutes a bearing for the spindle 20. The trip-dog carries a cam-block 23 which is arranged to ride upon a supporting pin 23' that extends from the engine cylinder wall and this sliding connection is adapted to 35 effect disengagement between the nose 17' of the trip-dog and the finger 18, whereby the jump-spark is produced as the contact between the electrodes is broken. This spark mechanism, however, forms no part of my present invention and is simply 40 shown to illustrate the general operation of the mechanism.

The lever 15' which is carried by the shank portion of the igniter bar, is provided for the purpose of lengthening and 45 shortening said bar, whereby the spark may be advanced or retarded, due to the predetermined position of the tappet-nose 17' with relation to the finger 18 as, for example, when the lever 15' is moved toward the 50 forward or cam end of the apparatus, the pitman portion 4'' is, through its connections to said lever, contracted with relation to the head portion of the rod and hence, in this contracted position, the moment of 55 ignition will be retarded and likewise should the lever be moved in the opposite direction, the sparking moment would be advanced, it being understood that the slot 60 16 is of such proportions as to permit the 65 slight arc movement of the pivot-pin 14'

which carries the pitman portion of the igniter rod. After the rod is adjusted as to length by the operator, it is locked in its position by a spring-controlled plunger 24, which plunger is carried by the lever 15' and has a transversely disposed foot 24' that engages notches 25 that are formed in the upper circular surface of the cheek-plates which constitute sectors. Should the speed of the engine be accelerated to a predetermined maximum number of revolutions per minute, it will be apparent that the governor-controlled stop-arm 10' will be depressed, whereby its nose end 10 is caused to come into the path of travel of the tappet-plate 9. Should the valve-rod be advanced by its cam to the limit of its movement, whereby the exhaust valve which it controls is opened, when the nose of the stop-arm is in this position it will be apparent 75 that said nose will engage the tappet-plate 9 and thus lock the rod in its extreme forward position as stated, whereby the exhaust valve, not shown, will be held open. Hence, as long as the speed of the engine 80 remains constant, the lock will prevent a charge of gas from entering the engine cylinder. Following this movement, it will be observed that after the spark-cam advances the igniter rod for a sparking operation, 85 upon retraction of the rod by its spring connection, its stop-lock 12'' will abut the tappet screw 12' of the valve-rod and thus prevent a full return movement of said igniter rod. Hence the igniter cam 6 will 90 impart no positive working stroke to the igniter rod while the valve-rod is locked. The operating mechanism is thus controlled, whereby the sparking mechanism is rendered inactive during a delay of the valve 95 movement, while, when the parts are operating to perform the ordinary charging, firing and compression cycle of the engine, they work independently of each other but when the valve-rod becomes inactive it simultaneously through its connection renders the sparking mechanism inactive. Hence it 100 will be seen that great scope of adjustment of the parts is effected to increase the capacity of the engine to its maximum. 105

As best shown in Fig. 3, the cam-block 23 is adapted to ride upon a flared sleeve 23'', which is revolubly mounted upon the pin 23', it being understood that said pin 23' is in the form of an eccentric, whereby it may 110 be raised or lowered to adjust the nose 17' of the dog with relation to the finger 18. By providing the loose sleeve revolubly mounted upon the cam pin 23', friction of the parts is eliminated whereby the device 115 120 will operate freely and without wear.

As shown, the cheek-plates 13 are provided with three notches *a*, *b* and *c*, the notches *a* and *c* being terminated with stop-ears 13'. When the adjusting lever 15' is 125 130

- locked in the center notch *b* by the finger 18, as shown in Fig. 1, the igniter rod is of such length whereby the spark moment is advanced to increase the power of the engine.
- 5 When it is desired to start the engine the actuating lever is shifted to the left, whereby it is locked in connection with the notch *a* causing the engine to spark over the center. Should it be desired to cut out the spark 10 and thus kill the engine, the lever is advanced to the right its extreme throw, whereby it will be locked in engagement with the notch *c*. Thus the rod will be distended in length and the trip-nose being beyond the point of engagement with the 15 sparking element it follows that the said sparking mechanism will be cut out, attention being called to the fact that the extreme movements of the actuating lever in 20 either direction are limited by the stop ears 13' of the cheek-plates.

I claim:

1. In an internal combustion engine, the combination with a reciprocative valve rod, 25 an independently reciprocative igniter rod and a common operating means for the rods associated with adjacent ends thereof, of a means for shortening and lengthening the igniter rod.
- 30 2. In an internal combustion engine, the combination of a housing, a valve rod slidably mounted in and projecting from the housing, an igniter rod slidably mounted in and projecting from the housing, means 35 within the housing for procuring outward movement of the rods, means resiliently urging the rods inwardly and means for shortening and lengthening the igniter rod associated with the intermediate portion thereof.

Copies of this patent may be obtained for five cents each, by addressing the "Commissioner of Patents, Washington, D. C."

3. In an internal combustion engine, an 40 igniter rod comprising a pair of sections, spaced cheek-pieces carried by one of said sections and provided with aligned slots, a lever including arms straddling the cheek-pieces and pivotally connected therewith at 45 their outside ends, a pin carried by said arms and extending through the cheek-piece slots, the other section of the rod being pivotally mounted upon the lever carried pin and means for adjusting and locking the lever 50 to hold the other section in extended or retracted position.

4. In an internal combustion engine, an igniter rod comprising a pair of sections, 55 spaced segmental cheek-pieces carried by one of said sections and provided with aligned slots and having notches in its upper peripheral edges, a lever including arms straddling the cheek pieces and pivotally connected therewith at their outer ends, a pin 60 carried by said arms and extending through the cheek-piece slots, the other section of the rod being pivotally mounted upon the lever carried pin, and means adapted to engage the notches of the cheek-pieces for adjusting and locking the lever to hold the 65 other section in extended or retracted position.

In testimony that I claim the foregoing I have hereunto set my hand at Milwaukee, 70 in the county of Milwaukee and State of Wisconsin, in the presence of two witnesses.

OLAF ELTON.
